UNITED STATES PATENT OFFICE.

EDWARD D. MAYBERRY, OF ALTA VISTA, VIRGINIA.

DESIGN FOR A RAILROAD-CROSSING SIGNAL.

47,190.

Specification for Design.

Patented Apr. 6, 1915.

Application filed January 11, 1915. Serial No. 1,699. Term of patent 3½ years.

To all whom it may concern:

Be it known that I, EDWARD D. MAYBERRY, a citizen of the United States, residing at Alta Vista, in the county of Campbell and State of Virginia, have invented a new, original, and ornamental Design for a Railroad-Crossing Signal, illustrated in the accompanying drawing, in which the figure is a front elevation of a railroad crossing constructed in accordance with the invention.

I claim:

The ornamental design for a railroad crossing signal, as shown.

E. D. MAYBERRY.

Witnesses:

E. B. HARRIS,
M. L. LANE.
